FIG. I

FIG. II

FIG. III

FIG. IV

INVENTOR:
Samuel McFarland,
by Arthur E. Baige,
Attorney.

UNITED STATES PATENT OFFICE.

SAMUEL MCFARLAND, OF COATESVILLE, PENNSYLVANIA.

CASTING APPARATUS.

1,290,614.

Specification of Letters Patent. Patented Jan. 7, 1919.

Application filed November 24, 1917. Serial No. 203,842.

To all whom it may concern:

Be it known that I, SAMUEL MCFARLAND, a citizen of the United States, residing at Coatesville, Pennsylvania, have invented a 5 certain new and useful Improvement in Casting Apparatus, whereof the following is a specification, reference being had to the accompanying drawing.

My improvement is particularly applicable 10 to internal stoppers for bottom-pour ladles, such as are used for casting steel. Ordinarily, such a stopper consists of a head of refractory, and incidentally frangible, material, such as graphitic cement, having a 15 socket molded therein with projecting portions, for instance, coarse screw threads, of such frangible material, fitted to directly detachably engage a complementary stopper rod, by which said head may be raised and 20 lowered, within the ladle, to open and close a nozzle outlet at the bottom of the ladle. The strain upon such frangible material incident to repeatedly reciprocating said rod, is such as to ultimately strip such threads 25 from the stopper head and permit it to fall from the rod and thus permit the accidental escape of the molten steel, with consequent loss and damage.

It is an object of my invention to so construct and arrange a stopper head of such 30 frangible material that it is impossible to separate it from the stopper rod by any stresses to which it may be subjected during the ordinary operation of the apparatus. 35 To that end; I provide a stopper head molded of graphitic cement or other suitable refractory material with a metallic shank permanently and rigidly embedded therein, and provide such shank with means to detachably engage the stopper rod.

My invention includes the various novel 40 features of construction and arrangement hereinafter more definitely specified.

In said drawing; Figure I is an elevation 45 of a stopper head and its appurtenances, conveniently embodying my improvement.

Fig. II is an elevation of said structure shown in Fig. I; at right angles to that view.

50 Fig. III is a plan view of said structure.

Fig. IV is a perspective view of a cast metal shank with a cross pin in unitary relation therewith.

In said figures: the stopper head 1 is molded of nonmetallic refractory material, 55 such as graphitic cement, and in rigid connection with a substantially flat metallic stopper shank 2 having a cross pin 3 extending transversely through it, embedded in said head and having two wedge slots 4 and 5 extending through said shank at respectively different distances from said head. Although I have found it convenient to make such shanks of cut sections of wrought iron bars, and to form such pins 65 separately therefrom and fit them together; it is to be understood that they may be otherwise formed, for instance, said shank may be a casting 6 with the cross pin in unitary relation therewith, as shown in Fig. IV. 70

The bifurcated coupling 7 is detachably fitted to said shank 2 and has two wedge slots, 8 and 9, extending through its bifurcations 10, in registry with the slots 4 and 5 of said shank. Said coupling also has the 75 outwardly projecting flange 12 at its end adjacent said head 1, and the socket 13 at its opposite end, with the wedge slot 15 extending transversely through it. The stopper rod 16 has its reduced lower end 17 80 detachably fitted to said socket 13, and has the wedge slot 18 extending transversely through it in registry with said slot 15 in said socket.

The wedges 20, 21 and 22 normally, 85 rigidly connect said shank, coupling, and rod, in the coöperative relation shown in the drawings.

As is well known to those skilled in this art; stopper rods for closures of this class 90 are usually provided with suitable sleeves 24 of graphitic cement, ganister or other refractory material. Said flange, 12, is conveniently provided on the coupling 7 aforesaid, to support the weight of such 95 sheathing material independently of said head 1.

Of course, the stopper rod might be directly fitted to the shank of the coupling above described. However, as such a rod 100 is approximately twelve feet long, whenever its end adapted for engagement with the shank became damaged, it would be more troublesome to transport it to and from the place where it must be repaired, 105 and to effect such repairs, than to manipulate

late the smaller bulk of the coupling aforesaid. Therefore, I prefer to employ such a coupling, merely for the purpose of facilitating repairs, and do not desire to limit myself to the specific details of construction thereof, which are not essential to the operation of my invention.

Of course, such heads must be of different sizes and shapes, to fit the various patterns 10 of ladle outlet nozzles. Moreover, it is to be understood that the shank, embedded in the stopper head, in accordance with my invention, may be shaped otherwise than as shown. For instance, it may be cylindrical, as shown in Fig. IV, and fitted in a correspondingly shaped socket in a stopper rod, or in an intermediate coupling. However, such construction and arrangement 15 would be more difficult to repair than that 20 which I have illustrated, at least with the facilities which are usually available where such apparatus is used. Moreover, the substantially flat form of stopper shank is advantageous, first, in that it resists stresses 25 tending to turn it in the stopper head to a greater degree than a cylindrical shank and, consequently, is not so apt to be accidentally loosened and, second, it is better adapted 30 for engagement with a bifurcated rod, than if it were otherwise shaped.

Therefore, I do not desire to limit myself to the precise details of construction and arrangement herein set forth, as it is 35 obvious that various modifications may be made therein without departing from the essential features of my invention as defined in the appended claims.

I claim:

1. In casting apparatus, the combination 40 with a stopper head, of nonmetallic refractory material, such as graphitic cement; of a substantially flat metallic stopper shank having a cross pin extending transversely through it, embedded in said head and having two wedge slots extending through said shank, at different distances from said head; a bifurcated coupling, detachably fitted to said shank, having two wedge slots extending through its bifurcations in registry with the slots in said shank, an outwardly projecting flange at its end adjacent said head, and a socket at its opposite end with a wedge slot extending transversely through it; a stopper rod detachably fitted to said socket, having a wedge slot extending transversely through it in registry with the slot in said socket; and wedges in said slots, rigidly connecting said shank, coupling and rod.
2. In casting apparatus, the combination 60 with a stopper head, of refractory material; of a substantially flat metallic stopper shank having a cross pin embedded in said head and having two wedge slots extending through said shank, at different distances from said head; a coupling, detachably fitted to said shank, having two wedge slots extending through its bifurcations in registry with the slots in said shank, an outwardly projecting flange at its end adjacent said head, and a socket at its opposite end with a wedge slot extending transversely through it; a stopper rod detachably fitted to said socket, having a wedge slot extending transversely through it in registry with the slot in said socket; and wedges in said slots, rigidly connecting said shank, coupling and rod.

ted to said shank, having two wedge slots extending through its bifurcations in registry with the slots in said shank, an outwardly projecting flange at its end adjacent said head, and a socket at its opposite end 70 with a wedge slot extending transversely through it; a stopper rod detachably fitted to said socket, having a wedge slot extending transversely through it in registry with the slot in said socket; and wedges in said 75 slots, rigidly connecting said shank, coupling, and rod.

3. In casting apparatus, the combination with a stopper head, of refractory material; of a metallic stopper shank permanently embedded in said head and having two wedge slots extending through said shank, at different distances from said head; a coupling, detachably fitted to said shank, having two wedge slots extending through its 85 bifurcations in registry with the slots in said shank, and a socket at its opposite end with a wedge slot extending transversely through it; a stopper rod detachably fitted to said socket, having a wedge slot extending transversely through it in registry with the slot in said socket; and wedges in said 90 slots, rigidly connecting said shank, coupling and rod.

4. In casting apparatus, the combination 95 with a stopper head, of refractory material; of a metallic stopper shank permanently embedded in said head; a coupling, detachably fitted to said shank, having an outwardly projecting flange at its end adjacent said 100 head; and a stopper rod detachably fitted to said coupling.

5. In casting apparatus, the combination with a stopper head, of refractory material; of a metallic stopper shank permanently 105 embedded in said head; a coupling, detachably fitted to said shank; and a stopper rod detachably fitted to said coupling.

6. In casting apparatus, the combination 110 with a stopper head, of nonmetallic refractory material, such as graphitic cement; of a substantially flat metallic stopper shank having a cross pin extending transversely through it permanently embedded in said head, so that it cannot be removed without 115 breaking said head, and having two wedge slots extending through said shank, at different distances from said head.

7. In casting apparatus, the combination 120 with a stopper head, of refractory material; of a substantially flat metallic stopper shank having a cross pin permanently embedded in said head, so that it cannot be removed without breaking said head, and having two wedge slots extending through said shank, 125 at different distances from said head.

8. In casting apparatus, the combination with a stopper head, of refractory material; of a metallic stopper shank permanently embedded in said head; and a coupling detach- 130

ably fitted to said shank, having an outwardly projecting flange at its end adjacent said head.

9. In casting apparatus, the combination with a stopper head, of refractory material; of a metallic stopper shank permanently embedded in said head; and a cross pin, distinct from said shank, but extending transversely through the latter, and permanently

embedded in said head; said shank being 10 substantially flat transversely to said pin.

In testimony whereof I have hereunto signed my name at Coatesville, Pennsylvania, this 21st day of November, 1917.

SAMUEL McFARLAND.
